UNITED STATES PATENT OFFICE.

LAZAR J. KELLNER, OF CHICAGO, ILLINOIS.

DESIGN FOR A RADIOCABINET.

Application filed June 23, 1924. Serial No. 9,946. Term of patent 7 years.

To all whom it may concern:

Be it known that I, LAZAR J. KELLNER, a citizen of the United States, residing in Chicago, county of Cook, and State of Illinois, have invented a new, original, and ornamental Design for a Radiocabinet, of which the following is a specification, reference being had to the accompanying drawing, forming a part thereof.

The figure is a perspective view of a radiocabinet showing my new design.

I claim:

The ornamental design for a radiocabinet as shown.

LAZAR J. KELLNER.
